(57) **CLAIM**

The ornamental design for a web camera, as shown and described.

DESCRIPTION

FIG. 1 is a front and right side perspective view of a web camera;

FIG. 2 is a front elevation view thereof;

FIG. 3 is a right side elevation view thereof;

FIG. 4 is a rear elevation view thereof;

FIG. 5 is a left side elevation view thereof; and,

FIG. 6 is a top plan view thereof.

The broken lines depict portions of the web camera in which the design is embodied and form no part of the claimed design.
